UNITED STATES PATENT OFFICE.

VIRGIL M. HADDON, OF OMAHA, NEBRASKA.

DUMPING TRUCK.

1,411,347.

Specification of Letters Patent.

Patented Apr. 4, 1922.

Application filed August 6, 1921. Serial No. 490,328.

To all whom it may concern:

Be it known that I, VIRGIL M. HADDON, a citizen of the United States, residing at Omaha, in the county of Douglas and State 5 of Nebraska, have invented certain new and useful Improvements in Dumping Trucks, of which the following is a specification.

This invention relates to an improvement in dumping-trucks, and has for its object, 10 broadly, to provide such a construction that the operation of dumping will be convenient, and that the parts required for this purpose will be few, simple and durable. The invention specifically includes means useful 15 for securing the front end of the box in locked relation with the frame of the truck in such a manner that vibration of the parts will be practically eliminated and accidental dumping will be prevented, also includes 20 convenient means for releasing the box to permit dumping, and one of the specific objects is to provide such a mounting for the tail-gate that leakage from the box will be prevented when closed, and that its upper 25 end will be moved upwardly and rearwardly during its swinging movement when the box moves to a dumped position. Also the invention includes certain adjustable features to be described.

30 In the accompanying drawing, Fig. 1 is a side view of a dumping truck embodying my invention, the front end of the box being elevated. Fig. 2 is a similar view showing the box in a lowered position. Fig. 3 is 35 a view of the front end of the box and parts mounted thereon, the spring for controlling the latch being broken away, the truck frame and parts of the cross-bar being partly in section, the section through the hand-lever being on line 3—3 of Fig. 2. Fig. 4 shows the reverse side of the dumping-truck 40 to that shown in Fig. 2. Fig. 5 is a sectional view on line 5—5 of Fig. 3, being a detail to clearly show the arrangement of a latch, 45 a catch, a spring and a crank-rod for disengaging the latch from the catch. Fig. 6 shows a plan view of a part of the truck-frame, together with a cross-bar, and means to adjust the cross-bar longitudinally of the 50 frame. Fig. 7 is a plan view, partly broken away, to illustrate the mounting of the tail-gate.

Referring now particularly to the drawing, the truck-frame and box thereon are 55 respectively indicated at 1 and 2, the pivotal mounting of the box, intermediate its

ends, preferably being upon a shaft 3 having bearings in the bosses 4 (Fig. 6.) of a pair of castings 5 which are secured upon the frame 1, at the rear end thereof.

60

Numeral 6 indicates a cross-bar which is disposed upon the top of the frame 1 and may be adjusted longitudinally thereof, said bar being secured to the frame, rearwardly of the driver's seat 7 by means of the pair 65 of staples 8.

The corners of the box 2, at its front end, are provided with posts 9 which extend below its bottom a suitable distance so that when the front end of the box has been 70 swung downwardly to its normal position, the lower ends of the posts will rest upon the top of the cross-bar 6.

Numeral 10 indicates the tail-gate. It is 75 provided with a pair of L-shaped brackets 11, each having an arm *a* which has a pivotal mounting 13 upon the top, inwardly from the rear end of the box.

Numeral 12 indicates a hand-lever disposed at one side of the truck, said lever having 80 a pivotal mounting *b* to permit swinging movements from a bracket 14, and at the opposite side of the truck is a lever 12' (Fig. 4.) having a pivotal mounting *b'* to permit swinging movements from a bracket 14', 85 said brackets 14 and 14' being mounted upon blocks 15 which are suitably secured to the cross-bar 6.

Numeral 16 indicates a link having its lower end mounted upon a pivot-pin *c*, carried by the hand-lever, its upper end being pivotally mounted, as indicated at *d*, upon the box. Numeral 16' (Fig. 4.) indicates a second link having its lower end mounted upon a pivot-pin *c'* which connects it with 95 the lever 12', its upper end being pivotally mounted upon the box, as indicated at *d'*.

Since the pivotal mounting *c* for the lower end of the link 16 is disposed midway between the ends of the hand-lever 12, an upward swinging movement of the latter will cause the front end of the box to swing upwardly for dumping, the lever 12' and link 16' having movements corresponding to the movements of said hand-lever and link 16. 105

Numerals 17 and 17' indicate a pair of pull-and-push rods which are pivotally mounted upon the respective ends of the tail gate, as indicated at 18, the front end of the rod 17 having a mounting upon the pivot-pin *c* and the rod 17' having a mounting of its front end upon the pivot-pin *c'*, and 110

it will be understood that the tail-gate will be opened by operation of the rods 17 and 17' when the hand-lever is swung upwardly, a downward swinging movement of the hand-lever, by operation of said rods 17 and 17' causing a closure of the tail gate.

In instances where the dumping-truck is used for hauling mortar, cement or other plastic material, it is necessary that a suitable closure may be made of the tail-gate, and therefore adjustable means are provided whereby a suitable degree of pressure may be maintained for said gate against the open, rear end of the box, and certain inclined plates are provided for the box which are adapted to be engaged by certain inclined surfaces of the gate, these features tending to prevent leakage.

Numeral 20 indicates a catch which is secured stationary upon the cross-bar 6, and at 21 is indicated a latch having a pivotal mounting *g* upon the front end of the box, and by means of a spring 22 which engages the latch, the latter will be engaged and maintained in engagement with the catch when the box has been swung downwardly to its normal position.

Means for releasing the latch from the catch consist of a crank-rod 23 (Fig. 3.) mounted to swing from brackets *h* which are secured to the posts 9, below the front end of the box, the projection or transverse loop *k* of the rod 23, when partly rotated, causing the latch to swing outwardly against the force of the spring 22 to permit said release.

The rod 23 may be conveniently rotated against the force of the spring 22 by an operator who may manually cause a rocking movement of the hand-piece 24, which is 40 pivotally mounted on the hand-lever 12, a flexible member or chain *m* being connected at one of its ends with the hand-piece 24, its opposite end being connected with the arm *n* of the rod 23.

It will be seen that the means described for maintaining the box in its normal, stationary position operate to advantage in resisting stresses, since the catch, latch and loop *k* of the rod 23 are disposed at the median line of the box.

Means are provided for maintaining the box in dumped position, consisting, in part, of a notched control-bar 25 adapted to slide in a loop, guide or catch-plate 26 which is secured to the side of the box, as shown in the drawing, the notches being adapted to engage said plate. This bar is pivotally mounted on the hand-lever, and by its use, the box may be maintained at various degrees of inclination, this last feature being of advantage to permit a gradual release of material from the box while the truck is driven forwardly to cause spreading of said material on the ground, in the operation of paving.

Means are provided for adjusting the cross-bar 6 longitudinally of the frame 1, consisting of the pair of adjusting-rods 27. By referring to Fig. 6 it will be seen that after the staples 8 have been loosened, the pair of nuts *p* may be rotated for making said adjustment, the rear ends of the rods 27 being in engagement with the castings 5, the advantage derived in making said adjustments being to dispose the bar 6 in such a position that the posts for the front end of the box will make suitable engagements therewith; also that the latch 21 may make suitable engagement with the catch 20, and also that the pivotal mounting *b* of the hand-lever 12 will be disposed at a suitable distance from the rear end of the box 1.

By referring to Fig. 3 it will be seen that the latch is threaded in the boss *r* of a pivotally mounted strap or holder *s* of the latch, and on that account the latter may be adjusted longitudinally so that it may suitably engage the catch.

It is considered that the means described for making the several adjustments are important. The parts may become unduly worn, and adjustments may be required. It is obviously an advantage to make such an accurate closure of the tail-gate that mortar or other plastic material will be retained in the box. While the inclined surfaces and flanges *e* are useful for said purpose, the hand-lever and rods 17 cause the actual pressure of the gate against the box, the parts being then disposed as shown in Fig. 2. Since the pivotal mounting *b* of the hand-lever may be adjusted longitudinally of the frame 1, it is obvious that the degree of pressure of the surfaces *f* of the tail-gate against the flanges *e* of the box may be regulated.

It will be appreciated that a truck for delivering different kinds of material must move upon various inclinations, and in some instances, during the operation of dumping it may be desired that the entire load shall be quickly emptied from the box, and on this account the tail-gate has such a mounting that its upper end will be elevated above the top of the box, which provides an ample passageway for material to be discharged.

Numerals 19 indicate plates which are secured to the box, the flanges *e* of the plates projecting rearwardly and outwardly at a suitable distance beyond the rear end of the box, the tail-gate 10 being provided with flat contact-surfaces or facets *f* which have such a degree of inclination that, when the tail-gate is closed, leakage of liquids will be prevented, a certain degree of pressure of the surfaces *f* against the inclined surfaces of the box being depended upon for this purpose.

While I have described details of construction, I do not wish to be understood as

limiting myself in this respect, and changes in size, form and proportion and minor details may be made, said changes being within the scope of the invention as claimed.

5 I claim as my invention:

1. The combination with a dumping-truck having a box mounted on the truck frame to permit it to have swinging movements, of a cross-bar on said frame, a catch on the 10 cross-bar approximately at the medial line of the frame, a latch pivotally mounted on the box normally engaging the catch, a rod having journalled bearings on the box and having a projection disposed at the medial 15 line of the frame, said rod being revoluble to move its projection for disengaging the latch from the catch.
2. The combination with a dumping-truck having a box mounted on the truck frame

to permit it to have swinging movements, of a catch approximately at the medial line of and secured to the frame, a latch-holder hingedly mounted on the box, a latch having a threaded connection with the latch-holder, a spring on the box normally causing engagement of the latch with the catch, a rod having journalled bearings on the box and having a projection disposed at the medial line of the frame, and means for rotating the rod to move its projection into 25 engagement with the latch for disengaging said latch from the catch.

In testimony whereof I have affixed my signature in presence of two witnesses.

VIRGIL M. HADDON.
